UNITED STATES PATENT OFFICE.

EMIL FUCHS, OF NEW YORK, N. Y., ASSIGNOR TO FRANCIS LYNDE STETSON, OF NEW YORK, N. Y.

DESIGN FOR A MEDAL.

40,250.

Specification for Design.

Patented Sept. 7, 1909.

Application filed June 29, 1909. Serial No. 505,110. Term of patent 14 years.

To all whom it may concern:

Be it known that I, EMIL FUCHS, a citizen of Austria, and a subject of the Emperor of Austria, residing at 80 West Fortieth street, in the city, county, and State of New York, have invented a new, original, and ornamental Design for a Medal, of which the following is a specification, reference being had to the accompanying drawing, forming part thereof.

I claim:

The ornamental design for a medal as shown.

EMIL FUCHS.
